UNITED STATES PATENT OFFICE.

HARRY ROSS, OF NEW YORK, N. Y., ASSIGNOR TO FUR GUIDE MACHINE CORPORATION, OF NEW YORK, N. Y., A CORPORATION OF NEW YORK.

NEEDLE PLATE FOR FUR-SEWING MACHINES.

Application filed August 18, 1926. Serial No. 129,898.

This invention relates to improvements in needle plates, and more particularly to needle plates used in fur sewing machines, as for instance, in the type of machine as shown in my Patent #1,541,751 issued June 9, 1925.

The main object of the invention is to provide means in a machine of this nature that will prevent the breaking of needles and the resultant loss of time in replacing and rethreading of the new needle.

Another object of the invention is to provide means for preventing the driven feed disk in a machine of this nature from tipping and rising on its bearing when the said bearing becomes worn.

A further object of the invention is to provide means for positively locating the needle plate in relation to the needle.

20 A still further object of the invention is to provide means for automatically expelling any dirt that may accumulate on the surface of the driven disk and prevent same from entering the disk bearing.

25 Other objects and novel features of my invention will become apparent as the specification proceeds.

In the drawings forming a part of this specification

30 Figure 1 is a view in side elevation of a machine of the type shown in my Patent #1,541,751 and

Figure 2 is a top plan view of the feeding disks portion of the machine.

35 Figure 3 is a section taken on line 3—3, Figure 2.

Figure 4 is a top plan view of my improved needle plate and

40 Figure 5 is a section taken on line 5—5, Figure 4.

Referring to the drawings in detail in which like numerals refer to the same parts throughout the several views, 10 indicates a fur sewing machine provided with a fly wheel 11 on a shaft 11^a, suitably connected to a source of power not shown. A needle bar 12 having a needle 13 is operated for sewing from the said shaft 11^a by the means shown in my Patent #1,541,751. A feed

45 disk 14 suitably mounted is driven in step by step motion by any suitable means (not shown) as the said means forms no part of my invention. Co-operating with the said feed disk 14 is a driven disk 15 normally held in resilient contact with the disk 14 by

a spring 16 on a rod 17 slidably supported in the walls 18 and 19 of the frame of the machine. Fixed to a bracket 20 is an arm 21 provided with a stud 22 upon which the disk 15 is rotatably mounted. The said 60 bracket 20 is prevented from turning by means of a lower rod 17^a fixed thereto and supported in the walls 18 and 19 of the frame of the machine.

As heretofore mentioned the disk 15 is rotatably mounted upon the stud 22 and is provided with a roller bearing 23. It is customary when feeding two strips of fur of uneven length between the disks 14 and 15, to form a collar or the like, to retard the 70 feeding movement of the disk 15 against which the shorter strip of fur bears, by exerting a pressure against the said disk by the hand of the operator. The said pressure together with the normal rotation of the 75 disk 15 causes considerable wear on the roller bearing with a consequent tipping upwardly of the inwardly disposed portion of the periphery of the disk 15 causing the needle 13 to strike the said disk and the said 80 impact will cause the needle to break. To prevent the said tipping of the disk and consequent breaking of the needle, I have provided the usual needle plate 25 with a groove 26 cut across its lower surface, and two short 85 grooves 27 in its upper surface. Into the said grooves 26 and 27 I insert a spring member 28 which exerts a downward pressure against the disk 15 and prevents same from tipping upwardly in the path of the 90 needle. The needle plate is secured to the stud 22 by a screw 29.

Another cause for the breaking of the needle is the fact that the said screw 29 becomes loose, thus allowing the needle plate 95 to become displaced, and bring the solid edges 30 of the said needle plate into the path of the needle and break the said needle when it comes into contact with the said edges instead of with the usual groove 31 100 provided in the said needle plate.

To prevent the said needle plate from coming out of proper alinement, the needle plate 25 is provided with an arm 25^a integral therewith or otherwise secured thereto, 105 having a projection 32 thereon fitting into a vertical groove 33 in the bracket 20. It will readily be seen that this arrangement will prevent any rotation of the needle plate on the screw 29 and will at all times main- 110

tain the groove in the needle plate in proper alignment with the needle and prevent the breaking of the needle. To prevent any undue wear of the roller bearing caused by 5 any particles of fur or dirt getting into the said bearing, I provide slots or openings 35 in the base of the disk 15. In Fig. 3 of the drawing I have shown the needle plate 25 undercut or spaced above the recessed surface of the disk 15. This space in actual 10 practice is only three or four thousandths of an inch to permit of a slight tensioning of the spring 28 when the disk tends to tip upwardly and to permit for slight variations 15 in the thickness of the spring material. For clearness of illustration, this space has been exaggerated. The distance between the 20 needle and the top surface of the disk is always greater than the distance between the bottom of the needle plate and the recessed surface of the disk. It will be seen that as the disk 15 revolves in the direction of the arrow, any dirt or particles of fur 25 and the like on the said disk will be swept out through the said openings by the needle plate 25.

From the foregoing it will be seen that I have provided positive means to prevent any upward tipping of the disk into the path of the needle, means for positively alining and maintaining the needle plate in proper position at all times to prevent any breaking of the needle, and that I have provided means for keeping the disk bearing free from any dirt or other foreign matter, thus reducing the wear on the said bearing.

Having described my invention, what I claim as new is:

1. In a sewing machine, a bearing, a material feeding disk, rotatably mounted on the

said bearing, a needle plate associated with the said feeding disk, a reciprocating needle associated with the disk, and a resilient member on the needle plate bearing against the disk to prevent the said disk from tipping upwardly into the path of the needle. 45

2. In a sewing machine, a bracket having a slot therein, a bearing post in said bracket, a feeding disk rotatably mounted on the bearing post, a needle plate mounted on said post, a reciprocating needle associated with the said plate, a groove in the needle plate in the path of the travel of the needle, and an arm on the needle plate fitting into the slot in the bracket to maintain the needle 50 plate in proper radial alinement with the needle.

3. In a sewing machine, a bracket, a bearing post in said bracket, a feeding disk rotatably mounted on the bearing post, a needle 60 plate mounted on said post, a reciprocating needle associated with the said plate, a groove in the needle plate in the path of the travel of the needle, a resilient member on the needle plate bearing against the disk to prevent the disk from tipping into the path 65 of the needle and an arm on the needle plate fitting into a slot in the bracket to maintain the needle plate in proper alinement with the needle. 70

4. In a sewing machine, a bearing post, a material feeding disk having openings therein, rotatably mounted on the post, and a needle plate mounted on the post adapted to sweep any foreign matter on the disk 75 through the said openings.

In testimony whereof I hereunto affix my signature.

HARRY ROSS.
